US00D929736S

(12) **United States Design Patent** (10) **Patent No.:** **US D929,736 S**
Dai (45) **Date of Patent:** **** Sep. 7, 2021**

(54) **CONTAINER**

(71) Applicant: **ShenZhen YiHong Technology Co., LTD**, Guangdong (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/744,511**

(22) Filed: **Jul. 29, 2020**

(51) LOC (13) Cl. **03-01**

(52) U.S. Cl.

USPC **D3/302**

(58) **Field of Classification Search**

USPC D3/201, 205, 242, 273, 274, 275, 276, D3/279, 281, 282, 284, 292, 294, 295, D3/296, 297, 299, 301, 302, 901, 903,

D3/905; D9/414, 418, 420–423, 425, 428

CPC A45C 5/04; A45C 11/00; A45C 11/16
